(57) **CLAIM**

The ornamental design for a diagnostic instrument, substantially as shown and described.

DESCRIPTION

This invention relates generally to instruments for performing diagnostic analysis on a variety of liquid samples, particularly biological samples.

FIG. 1 is perspective elevational view illustrating a first embodiment of the diagnostic instrument in accordance with this invention in a fully closed position.

FIG. 2 is a top view of the diagnostic instrument of FIG. 1. FIG. 3 is a bottom view of the diagnostic instrument of FIG. 1.

FIG. 4 is a front elevational view of the diagnostic instrument of FIG. 1.

FIG. 5 is a rear elevational view of the diagnostic instrument of FIG. 1.

FIG. 6 is side elevation view of the diagnostic instrument of FIG. 1; and,

FIG. 7 is another side elevation view of the diagnostic instrument of FIG. 1.
